ADJUSTABLE SHELVING BRACKET

Walter L. Slater, Watsonville, Calif., assignor to
Slater Shelving System, a corporation of California

Application March 21, 1934, Serial No. 716,716

8 Claims. (Cl. 248—243)

This invention relates to certain new and useful improvements in adjustable shelving brackets.

The primary object of the invention is to provide adjustable shelving brackets for mounting upon a standard or upright support and of the type embodying a horizontal arm for the support of a shelf board and a vertical limb to facilitate mounting of the bracket upon the upright support.

A further object of the invention is to provide adjustable shelving brackets embodying horizontal arms and vertical limbs for mounting upon an upright support with the brackets pivotally supported on the upright at its angle corner or juncture of the horizontal arm and vertical limb and having a tilting screw arrangement associated with the lower end of the vertical limb and cooperating with the upright support for positioning the horizontal arm in a true horizontal plane, or at an inclination if desired.

A further object of the invention is to provide adjustable shelving brackets of the foregoing character wherein a series of uprights for the support of the shelving brackets has the uprights connected together by brace bars extending between the uprights and anchored at their ends thereto with a floor supported board projecting forwardly of each upright for the mounting of a bottom shelf and front end finishing panel.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a fragmentary front elevational view of an adjustable shelving bracket construction in accordance with the present invention,

Figure 2 is a fragmentary side elevational view of one of the upright supports with the shelf board and base shelf shown in section;

Figure 3 is a fragmentary side elevational view of an upright support with a shelving bracket projecting therefrom;

Figure 4 is a fragmentary front elevational view of an upright support with the shelving bracket in position thereon and illustrating the saddle on the horizontal arm of the bracket for the support of shelf ends;

Figure 5 is a top plan view of the shelving bracket with the upright support shown in section;

Figure 6 is a vertical sectional view taken on line 6—6 of Figure 4, showing the pivot pin con-

nection between the shelving bracket and upright support and the tilting screw device associated with the lower end of the vertical limb of the shelving bracket and the upright support;

Figure 7 is a fragmentary elevational view of the opposite face of the lower end of the vertical limb of the shelving bracket and tilting screw construction;

Figure 8 is a cross-sectional view taken on line 8—8 of Figure 6;

Figure 9 is a detail sectional view taken on line 9—9 of Figure 6;

Figure 10 is a fragmentary front elevational view, similar to Figure 1, showing brace bar connections between upright supports, positioned rearwardly of a facing or finishing panel;

Figure 11 is a vertical sectional view taken on line 11—11 of Figure 10, showing the angle members connecting the brace bars to the upright support;

Figure 12 is a detail sectional view of the upper end of an upright support, showing the interlocking connection between the angle member and support for the attachment of the upper brace bar;

Figure 13 is a front elevational view of an angle member for connecting brace bars to the upright supports intermediate the upper and lower ends thereof;

Figure 14 is a side elevational view of a spacer clip for attachment to the horizontal arm of the bracket between the upright support and adjacent end of the shelf board supporting saddle;

Figure 15 is a perspective view of another form of shelving bracket provided with an upper edge lateral flange for the support of shelving boards intermediate their ends as shown in Figure 1;

Figure 16 is a fragmentary elevational view of another form of tilting screw construction with the tilting screw in the plane of the vertical limb of the shelving bracket;

Figure 17 is an edge elevational view of the device shown in Figure 16; and

Figure 18 is a fragmentary plan view of the lower end of the vertical limb of the bracket shown in Figure 16, to facilitate attachment of the tilting screw.

Referring more in detail to the accompanying drawings, the reference character 20 designates an upright support upon which shelving brackets 21 and 21a are adjustably mounted.

The upright support 20 as shown more clearly in Figures 5, 6, 8 and 9, is of tubular or channel formation, rectangular in formation and having a rear wall 22, side walls 23, spaced front

walls 24 with an inwardly directed flange 25 at the free edge of each front wall 24 with the inner edges of the flanges 25 notched as at 26 to provide seats for lateral pins carried by the 5 shelving brackets 21 and 21a. The spaced walls of the notches 26 are slightly inclined upwardly and rearwardly for the more secure seating of the shelving brackets, as shown in Figure 6.

The shelving bracket 21 is shown in Figs. 3 10 and 6 comprises a horizontal arm 27 and a vertical limb 28, the bracket being of one-piece construction and of blade-like form. Laterally directed pins 29 are carried by the upper end of the vertical limb 28 and when the vertical limb 15 is disposed in the upright channel member 20, the pins 29 are seated in selected notches 26.

A tilting screw arrangement is associated with the lower end of the vertical limb 28 and the upright channel support and as shown more clearly in Figures 6 to 8, comprises a plate 30 flatly engaged with one side of the lower end of the vertical limb 28 and carrying end lugs 31 reversely bent to overlie the opposite face of the lower end of the vertical limb 28 as shown in 25 Figure 6. An offset tubular member or barrel 32 is carried by the plate 30 and extends transversely of the vertical limb 28 and said barrel has a transverse opening intermediate its ends that registers with a similarly formed opening 33 in the vertical limb 28. A nut 34 extends into the opening in the barrel 32 and also projects into the opening 33 in the vertical limb while the screw 35 freely movable through the barrel 32 is threaded to the nut 34 and forms an interlocking 30 connection between the tilting screw plate 30 and the vertical limb 28 of the bracket. The screw 35 is provided with a relatively large head 36 and constitutes the tilting screw for the adjustment of the horizontal arm 27 of the shelving 35 brackets 21 and 21a. With the shelving brackets in position in the upright channel support, the tilting screw head 36 projects outwardly of the support and forwardly of the front wall 24 thereof and said tilting screw head 36 is 40 adapted to be engaged with an abutment strap 37 of U-shape as shown in Figure 8 that straddles the forward side of the upright channel support and is provided with a lower end opening slot 38 to facilitate placement thereof on the upright channel support rearwardly of the tilting screw head 36. Upon operation of 45 the tilting screw 35, the shelving brackets 21 and 21a are shifted on their pivot pin mountings 29 for the correct positioning of the horizontal arms 27 thereof.

From an inspection of Figures 6 and 7, it will be observed that the tilting screw 35 is positioned laterally of the vertical limb 28 of the shelving bracket and another form of tilting screw which positions the same in the plane of the vertical limb 28 of the bracket is shown in Figures 16 to 18. The lower end of the vertical limb 28 of the shelving bracket is provided with side notches 39 and a lower end notch 40. A U-shaped clip comprising side plates 41 and 42 is placed upon the lower end of the vertical limb 28, the plate 42 being cut away at its corner edges as at 43 and shown by dotted lines in Fig. 16, these cut-away portions registering with the side notches 39 in the vertical limb while the plate 41 of the clip carries lateral lugs 44 at its free corners that are adapted to be bent for reception in the side notches 39 and to overlie the plate 42 as illustrated, this connection securing the clip element of the tilting screw upon the lower 75

end of the vertical limb. The outer end of the clip is in the form of a tubular barrel 45 that carries the side plates 41 and 42 and said barrel is provided with a transverse opening intermediate its ends for the reception of the nut 46 that extends into the end notch 40 in the vertical limb, the tilting screw 47 freely passing through the barrel 45 and threading through the nut 46 and provided upon its outer end with a relatively large abutment head 48. The foregoing tilting screw arrangement presents the tilting screw in the plane of the vertical limb 28 of the shelving bracket.

A saddle 49 of U-shape in end elevation is received upon the upper side of the horizontal arm 27 of the shelving bracket, being bolted or otherwise secured thereto as at 50 and provided with laterally directed flanges 51 at the lower ends of the sides thereof for the support of the adjacent ends of shelf boards, the shelf boards 20 being of a thickness to present the upper edge of the saddle 49 in the plane thereof. The flanges 51 of the saddles 49 are provided with key-hole slots 52 to receive lug pins depending from the shelf board for the anchoring of the 25 latter to the flanges, but it is to be understood that other forms of fastening means may be provided. The shelf boards are designated by the reference character 53.

To retain the shelving brackets rigidly positioned upon the upright channel support, there is provided a spring clip or spacer shown in detail in Figure 14 and comprising a pair of legs 54 carried by a loop head 55, one of the legs being longer than the other to facilitate placement thereof upon the bracket. The spring or spacer clip has the legs 54 thereof straddling the horizontal arm 27 of the bracket between the forward side of the upright channel support 20 and the adjacent end of the saddle 49 and when so disposed, movement of the shelving bracket relative to the upright channel support is prevented, the spring clip acting to prevent displacing movement of the pin support 29 relative to the notches 26. When it is desired to vertically adjust the shelving brackets 21 and 21a with respect to the upright channel support 20, the spring or spacer clip is disengaged from the bracket whereupon pins 29 may be moved further rearwardly into the upright channel support to be displaced from the notches 26 so that the vertical limb 28 of the bracket may be shifted in the upright channel support and the pins 29 positioned in a selected notch 26. The spring or spacer clip is then replaced and the shelving bracket is again rigidly mounted upon the upright channel support.

The saddles 49 are desired for the support of shelf board ends and it is also intended to employ the form of shelving bracket 21 shown in detail 60 in Figure 15 for the support of shelf boards intermediate their ends. The bracket 21a is provided on the upper edge of its horizontal arm 27a with a laterally directed angle flange 51a and the shelf boards are suitably anchored thereto. The bracket 21a is provided with laterally directed pins 29a for the support thereof in flange notches 26 and the vertical limb 28a of the bracket is provided with a slotted opening 33a, side notches 39a and an end notch 40a to facilitate attachment 70 thereto of either form of tilting screw arrangement shown in Figures 6 to 9 or Figs. 16 to 18.

The several upright channel members of a unit may be connected by brace bars, as shown in Figs. 10 and 11, the connection between the upper ends 75

5 of adjacent upright supports including angle clips each having a horizontal flange 56 and an inverted U-shaped vertical flange 57 to straddle the upper end of a side wall 23 of the upright support. The upper end of the upright support is closed by a vertical flange 57 is provided with an indenture 58 to receive a finger 59 struck-out from the vertical member 57 to retain the angle clip in position against displacement. A brace 10 bar or rod 60 is secured at its ends to the horizontal flanges 56 of the angle clips. The upright supports are further connected by brace bars 60 intermediate their upper and lower ends by means of angle clips, each including a horizontal flange 15 61 and a depending flange 62, the latter being provided with lower end opening notches 63 tapering toward their upper ends and communicating with cross slots 64 to permit positioning of an anchor screw in either end of the slot for the rigid 20 mounting of the angle clip. The brace rod or bar 60 is anchored at its ends to the upper sides of the horizontal flanges 61.

25 Perpendicular brace boards 65 each has an end thereof positioned in the lower end of the upright channel support and anchored therein by transverse fastening elements 66 and said boards 65 have secured to their upper edges a lower rigid shelf board 67 and a front end finishing board or panel 68. The adjustable shelving 30 brackets and support may be used for original installation, but it is primarily intended that they be employed for replacement work and in such instances, the upright channel support may be anchored in any convenient manner to a wall and a front finishing panel 69 positioned between 35 adjacent upright supports and substantially in line with their forward edges as illustrated in Figs. 10 and 11 so that the upright supports are hidden from view except for the forward open 40 sides thereof.

45 From the above detailed description of the invention, it is believed that the construction and use thereof will at once be apparent and while there are herein shown and described the preferred embodiments of the invention, it is nevertheless to be understood that minor changes may be made therein without departing from the spirit and scope of the invention as claimed.

50 I claim:—

55 1. In an adjustable shelving bracket, an upright channel support, a bracket having a horizontal arm and a vertical limb, a pin and notch connection between the angle portion of the bracket and the forward side of the upright support, the vertical limb disposed inwardly of the upright channel support, and means associated with the lower end of the vertical limb and upright support for tilting the bracket on its pin and notch support for presenting the horizontal 60 arm of the bracket in the desired plane, the tilting means including a screw carried by the vertical limb within the channel support and the head of said screw projecting exteriorly of the channel support for contact with the outer face thereof.

65 2. In an adjustable shelving bracket, an upright channel support, a bracket having a horizontal arm and a vertical limb, a pin and notch connection between the angle portion of the bracket and the forward side of the upright support, the vertical limb disposed inwardly of the upright channel support, means associated with the lower end of the vertical limb and upright support for tilting the bracket on its pin and

70 notch support for presenting the horizontal arm of the bracket in the desired plane, the tilting means including a screw carried by the vertical limb within the channel support and the head of said screw projecting exteriorly of the channel support for contact with the outer face thereof, and an abutment member interposed between the screw head and upright support. 75

3. In an adjustable shelving bracket, an upright channel support, a bracket having a horizontal arm and a vertical limb, a pin and notch connection between the angle portion of the bracket and the upright support, the vertical limb disposed inwardly of the upright channel support, means associated with the lower end of the vertical limb and upright support for tilting the bracket on its pin and notch support for presenting the horizontal arm of the bracket in the desired plane, the tilting means including a clip plate mounted on the vertical limb, a barrel on one side of the plate having a cross opening therein, said vertical limb having an opening with which the cross opening registers, a nut extending into both openings, a headed screw in the barrel threaded through the nut and securing the clip plate to the limb and said screw head positioned exteriorly of the upright support for contact therewith.

35 4. In an adjustable shelving bracket, an upright channel support, a bracket having a horizontal arm and a vertical limb, a pin and notch connection between the angle portion of the bracket and the upright support, the vertical limb disposed inwardly of the upright channel support, and means associated with the lower end of the vertical limb and upright support for tilting the bracket on its pin and notch support for presenting the horizontal arm of the bracket in the desired plane, the tilting means including a clip plate attached to the lower end of the vertical 40 limb, a barrel carried by the clip plate at the end thereof in line with the vertical limb, a nut intermediate the ends of the barrel and a headed screw in the barrel threaded through the nut with the head positioned exteriorly of the upright support 45 for contact therewith.

50 5. In an adjustable shelving bracket, the combination with an upright support, of a bracket having a horizontal arm and a vertical limb vertically adjustably mounted on the upright support, and adjustable means carried by the bracket and engageable with the upright support for tilting the bracket on its mounting for presenting the horizontal arm of the bracket in the desired plane, said means including a tubular element extending transversely of the lower end of the vertical leg, a headed screw freely mounted in the tubular element and a nut carried by the headed screw intermediate its ends and interlockingly engaged with the tubular element, the screw threading through the nut with the head thereof engaged with the outer face of the upright support for placing the horizontal arm in the desired plane.

55 6. In an adjustable shelving bracket, the combination with an upright support, of a bracket having a horizontal arm and a vertical limb vertically adjustably mounted on the upright support, and adjustable means carried by the bracket and engageable with the upright support for tilting the bracket on its mounting for presenting the horizontal arm of the bracket in the desired plane, said means including a rolled tubular element extending transversely of the lower end of the ver- 75

tical leg and in the plane of the leg, a headed screw freely mounted in the tubular element and a nut carried by the headed screw intermediate its ends and interlockingly engaged with the tubular element, the screw threading through the nut with the head thereof engaged with the outer face of the upright support for placing the horizontal arm in the desired plane.

7. In an adjustable shelving bracket, the combination with an upright support, of a bracket having a horizontal arm and a vertical limb vertically adjustably mounted on the upright support, and adjustable means carried by the bracket and engageable with the upright support for tilting the bracket on its mounting for presenting the horizontal arm of the bracket in the desired plane, the bracket mounting including pins and notched seats therefor between the bracket and upright support, shelf board supports carried by the horizontal arms and terminating in spaced relation to the upright supports when the brackets are in operative position and a spacer element mounted on the horizontal arm between the shelf board

supports and upright supports for holding the pins immovable in the notched seats.

8. In an adjustable shelving bracket, the combination with an upright support, of a bracket having a horizontal arm and a vertical limb vertically adjustably mounted on the upright support, and adjustable means carried by the vertical limb of the bracket at a point below the bracket mounting and engageable with the upright support for tilting the bracket on its support for presenting the horizontal arm of the bracket in the desired plane, the bracket mounting including pins and notched seats therefor between the bracket and upright support, shelf board supports carried by the horizontal arms and terminating in spaced relation to the upright supports when the brackets are in operative position and a spacer element mounted on the horizontal arm between the shelf board supports and upright supports for holding the pins immovable in the notched seats.

WALTER L. SLATER.
